CLAIM

The ornamental design for garden edging, as shown and described.

DESCRIPTION

FIG. 1 is front elevational view of the garden edging of our design;

FIG. 2 is a rear elevational view thereof;

FIG. 3 is a top plan view thereof;

FIG. 4 is a bottom plan view thereof;

FIG. 5 is an enlarged front perspective view of a portion thereof;

FIG. 6 is an enlarged rear perspective view of a portion thereof; and,

FIG. 7 is an enlarged partial perspective view from the rear showing the connection of two products.

The broken lines are for illustrative purposes only and form no part of the claimed design.
